UNITED STATES PATENT OFFICE.

MIGUEL SANTALÓ, OF BARCELONA, SPAIN.

MACHINE FOR TREATING SKEINS OF THREAD.

Application filed July 8, 1922. Serial No. 573,735.

To all whom it may concern:

Be it known that I, MIGUEL SANTALÓ, subject of the King of Spain, residing at Barcelona, Spain, have invented certain new and useful Improvement in Machines for Treating Skeins of Thread, of which the following is a specification.

My invention relates to the machines for treating skeins of thread, that is to say, submitting the skeins to the operations of bleaching, dyeing and finishing. Various machines are utilized in the industrial world for the above said treatment, though not one has obtained a regular impregnation of the liquor on the plurality of textile fibers, or if this impregnation is regular, the production of the machine is small.

One of the subject matters of my invention is to obtain a machine for treating skeins of thread, operating the decoction, bleaching, dyeing and finishing, by which the impregnation of the skeins is effected with regularity and quickness at the same time.

Another of the subject matters consists in obtaining a machine of this kind, of strong and simple building, resistant against deterioration and submitting automatically the skeins to the various operations as impregnation, compression, wringing, airing and so forth, working in a continuous manner and treating a great number of skeins at a given time.

My improved machine consists of a vat containing the bath,—dyeing, bleaching or finishing bath—into which are placed a plurality of pairs of rollers in a manner so that the upper roller of each pair is supported by slideable bearings. In combination with these rollers, comprises the machine two endless parallel chains, suitably separated and provided with hooks duly distributed thereon, with which are engaged the ends of rods on which hang the series of skeins to be treated. These chains attach the rods in a manner that they always present themselves edgeways in the path of the direction of the chain movement and are guided in appropriate manner for conducting the skeins through a zigzag line until and across the various pairs of rollers disposed in the vat containing the bath for treating the skeins.

There is also provided a pair of rubber

compression rollers at one end of the vat, disposed in order to extract the liquor from the skeins on their leaving the bath.

After having the liquor removed, the skeins are exposed to the action of the air for their oxidation, if it is a question of dyeing, or for their hardening and drying if it is a question of finishing the same.

The exposition to the action of the air ended, the skeins are withdrawn from the machine to be substituted for new ones or are left yet on the chain to submit them to a second passing in the machine.

The invention will be fully described in accordance with the accompanying drawings showing a machine which embodies my invention;

Fig. 1 is a side elevation of the machine.

Fig. 2 is a vertical longitudinal section along the line II—II of Fig. 3.

Fig. 3 is a vertical cross section along the line III—III of the Fig. 1.

The machine consists of a vat 2 containing the dyeing, bleaching or finishing bath with which the skeins have to be treated. Inside the vat 2 there are positioned pairs of rollers 8, 9, suitably distributed lengthwise of the vat. Each pair of rollers 8, 9, is supported by bearings 4 constructed in the known manner wherein the axle of the lower roller 9 is supported in fixed bearings and the axle of the upper roller 8 is supported in bearings 10, slidably mounted in the bearings 4 and moved by means of a small screw-threaded spindle which passes through the column 7 of the support and terminates in the bevel pinions 11 which engage with the pinions 11' mounted on the shaft 13'. In order to impart movement to the upper bearings on both sides of the machine the shaft 13' is provided with a hand wheel 12. In this way the pressure which the upper rollers 8 exercise upon the lower rollers 9 is regulated and consequently the pressure upon the skeins 39 subjected to treatment.

At the extreme end of the vat 2 there are arranged outside of the bath two compressor rollers 14, 15. The axle 16 of the roller 14 is supported in fixed bearings and the axle of roller 15 is supported in a movable bearing 26 the position of which can be adjusted by means of the spindle 27 and fly-wheel 28.

with interposition of a helicoidal spring 29 so as to be able to graduate in an elastic manner the pressure which the roller 15 has to exert upon the roller 14.

5 These rollers 14, 15, are situated immediately above the bath, so that the wringing out of the skeins takes place when they are in a vertical position and before the liquid of the bath has had time to become altered 10 or oxidized. Consequently the liquid when wrung out again falls back into the bath and is used afresh. If necessary a casing may be arranged to surround the rollers 14, 15, so as to isolate the skeins from contact 15 with the air as far as possible whilst they are being wrung out.

There is also combined with the machine a pair of chains represented in the drawing by the lines 3, 3'. These chains are at a distance 20 corresponding to the width of the machine and have hooks suitably distributed thereon, with which are engaged the ends of rods 38 which guide the series of skeins 39 to be treated. These chains are guided 25 by pulleys or chain wheels 20 so that they change their direction, passing from the horizontal to the vertical, and the rods 38 which contain the skeins 39 are so attached to the chains that they always present themselves edgewise in the path of the direction 30 of movement. However when the chains 3, 3' change their direction the rods 38 make part of a turn thus automatically changing the points of contact of the skeins 39 with the rods 38 and thus causing the threads to be uniformly impregnated over 35 their whole length.

The pulleys or wheels 20 do not communicate movement to the chains 3, 3' but they 40 merely serve as a guide and, to this end, they are loosely mounted upon their respective axles. The guide wheels 40 stretch the chains in the manner already known and on passing by these guide wheels, the rods 45 38 can be removed from the chains together with the treated skeins and fresh rods with skeins may be attached to the chains. Nevertheless in practice it is preferable to prolong the path which the chains follow and to 50 arrange a point for removing the rods with the skeins already treated and another for adjusting the rods loaded with fresh skeins.

The rods provided with skeins follow the movement indicated by the arrows 19 and 55 pass over the roller 21 which guides them to the rollers 8, 9. These latter rollers cause the rods to make successive zigzag turns up to the guide roller 22 which directs them to the wringing out rollers 14, 15. This operation 60 is repeated several times if necessary and as, within the same bath, the chains change their direction several times the rods 18 also change their position thus altering the points of contact of the rods with 65 the skeins and thus allowing of a thorough

impregnation with liquid of the parts of the thread which have not been sufficiently bathed during the previous operation through having been in contact with the rods.

70 Power is supplied to the machine through the pulley 23 mounted on the shaft 16 and by means of the wheels 17 and chain 17' it is transmitted to the upper axle 5. From this latter through the gearing 6 it is transmitted to the axle 24 of the pulley 25 which actuates the chain 3 on one side of the machine and through the gearing 6' the movement is transmitted to the axle 24' of the pulley 25' which moves the chain 3' on the 75 opposite side of the machine. 80

At the opposite end of the axle 16 there is a chain pulley 30 which by means of a chain 31 transmits power to a pulley 32 mounted on the axle 33 supported at this end by a bearing 34. At this end the axle 33 carries a toothed or gear wheel 35 which by means of intermediate pinions 36 imparts a rotary movement to wheels 37 mounted on the axles 9. 90

The number of teeth on the wheels 30, 32, is so calculated that the rollers 8, 9 rotates with a peripheral velocity slightly greater than that which the wheels 25, 25' communicate to the chains 3, 3'. The result of this is 95 that the skeins 29 on passing between the rollers 8, 9 are fed slightly forward of the rod 38 which guides them and, consequently, the fold of the skein fails to come into contact with the edge of the rod and the liquid 100 in the bath thereby penetrates into the fold of the skein.

I claim:

1. A machine for treating skeins, having in combination, a vat containing the bath, 105 a plurality of pairs of rollers, the upper roller of each pair being adjustable, two endless parallel chains following a path partly inside and partly outside of the bath, a pair of positively driven pulleys to impart 110 motion to said endless chains, wheels for guiding said endless chains outside of the bath, wheels for guiding said endless chains inside of the bath and mounted loosely on the axles of said rollers inside 115 of the vat so as to allow the skeins carried by said chains to follow a zigzag course while passing through the pairs of rollers, and driving mechanism to set in motion said rollers contained inside of 120 the bath at a peripheral speed slightly greater than that of the chains.

2. A machine for treating skeins, having in combination: a vat containing the bath, 125 a pair of endless parallel chains following a course partly inside and partly outside of the bath, a plurality of pairs of rollers contained in the bath positively driven at a peripheral speed slightly greater than that of the chains, the upper roller of each pair of 130

- rollers being adjustable, a plurality of wheels or pulleys mounted loosely above the axles of said rollers to guide the chains following a zigzag path within the bath, skein extract from the skeins the excess liquor 10 and allow said liquor to drop into the vat.
- 5 carrying rods engaged by hooks attached to the endless chains, so that the surface of the rod corresponds with the direction of the motion, and a pair of wringing rollers placed immediately above the bath so as to

In testimony whereof I affix my signature.

MIGUEL SANTALÓ.
